(57) **CLAIM**

The ornamental design for a portable oxygen concentrator, as shown and described.

DESCRIPTION

FIG. 1 is a right perspective view of the portable oxygen concentrator of the present design;

FIG. 2 is a front view of the portable oxygen concentrator of the present design;

FIG. 3 is a rear view of the portable oxygen concentrator of the present design;

FIG. 4 is a right side view of the portable oxygen concentrator of the present design;

FIG. 5 is a left side view of the portable oxygen concentrator of the present design;

FIG. 6 is a top view of the portable oxygen concentrator of the present design; and,

FIG. 7 is a bottom view of the portable oxygen concentrator of the present design.

The broken lines showing additional features of the portable oxygen concentrator in FIGS. 1–7 are for illustrative purposes only and form no part of the claimed design.
